UNITED STATES PATENT OFFICE.

JULIUS HUGO SKOGMAN, OF JOPLIN, MISSOURI.

RAILWAY-SWITCH.

1,358,887.

Specification of Letters Patent. Patented Nov. 16, 1920.

Application filed June 15, 1920. Serial No. 389,095.

To all whom it may concern:

Be it known that I, JULIUS H. SKOGMAN, a citizen of the United States, and a resident of Joplin, in the county of Jasper and State of Missouri, have invented certain new and useful Improvements in Railway-Switches, of which the following is a specification.

The present invention relates generally to 10 railway switches and more particularly to a railway switch lock.

The object of the invention is to provide 15 a switch lock which engages the switch points and locks the same in set position independently of the switch stand or other operating means usually associated with the switch points for controlling them as to movements and positions, to thereby preclude any possibility of splitting of the 20 switch—due to the high speed of the passing train, to failure of the switch stand or other control to properly operate, or to other reasons.

Another important object is to provide a 25 switch lock of this character of simple and durable construction, reliable in operation and easy and inexpensive to manufacture and which is endowed with features of resiliency which enable it to receive the forces 30 incident to the passing of a train and to withstand the action of these forces without having destructive stresses set up in any of its component parts.

Other objects and advantages of the invention reside in certain novel features of 35 construction, combination and arrangement of parts which will be hereinafter more fully described and particularly pointed out in the appended claims, reference being had 40 to the accompanying drawings forming part of this specification, and in which:

Figure 1 is a plan view of a switch embodying my invention;

Fig. 2 is a side elevation thereof;

Fig. 3 is a transverse vertical section;

Fig. 4 is a detail view in transverse vertical section of the keeper for the operating bar;

Fig. 5 is a detail view in transverse section of the resilient mounting for the rock shaft;

Fig. 6 is a detail perspective view of a lock lug associated portion of the rock shaft; and

Fig. 7 is a detail perspective view of the keeper for the operating bar.

Referring to the drawings it will be seen that the invention contemplates a railway embodying stock rails R and switch points provided with wear surfaces s at their outer ends. A connecting rod C which leads to a standard form of switch control such as a switch stand (not shown) serves to normally control the switch points both as to movement and position and constrains both switch points to corresponding motion.

A rock shaft 10 is journaled for rotary and sliding movement in bearings 12 provided therefor in the stock rails. The rock shaft carries adjacent each stock rail a lock lug 13, one for each switch point. Each of these lock lugs consists of a hub 14 which is provided with a squared or polygonal shaped opening 15 therethrough which receives the polygonal shaped portion 16 of the rock shaft to constrain the lock lug to partake of all rotary motion of the rock shaft while permitting it to be free of the rock shaft with respect to any longitudinal movement thereof. Thus the lock lug may be said to 80 be splined to the rock shaft. The locking portion 13' is formed integral with the hub and is generally rectangular in cross section. Each of the lateral point engaging faces of the lock lug is provided with an inclined 85 surface 17 which constitutes a guide for camming the operative lateral face 18 into engagement with the switch point. A spacing sleeve 19 is mounted on the rock shaft between the pair of lock lugs and maintains 90 them in proper spaced relation.

One end of the rock shaft carries the operating bar 20 which is secured thereto by a cotter pin or similar means 21 and which serves to oscillate the rock shaft and consequently the lock lugs into and out of engagement with the switch point. The operating bar is provided with a longitudinal slot 22 which is adapted to receive the staple 23 of the keeper 24. The staple is provided 100 with an aperture 25 adapted to receive the shackle of a pad lock or the like (not shown). A stop shoulder 26 is provided on the keeper for limiting the downward movement of the operating bar. As shown in 105 Fig. 4 the keeper is carried by the base of the rail and has its side walls secured to the web of the rail by a bolt and nut 27.

Means are provided for limiting the transverse movement of the rock shaft while permitting it to partake of a certain amount of such movement. This means comprises a

coil spring 28 which is arranged upon the end of the rock shaft, as shown in Fig. 3. The inner end of the coil spring is abutted or stopped by the web of the adjacent stock rail. A collar 29 is carried by the outer end of the rock shaft being secured thereto in any suitable manner as by a cross pin 30 and serves as an abutment for the outer end of the coil spring. Preferably however a housing 10 is provided for the coil spring and the associated portion of the rock shaft and comprises a cylinder 31 having an inturned annular flange 32 at its inner end which receives the direct pressure of the inner end of the coil spring and transmits this pressure to the web of the stock rail. The outer end of the cylinder is exteriorly threaded, as shown, to receive the cap 33.

In practice if it is desired to move the switch points the lock lugs are rotated in a clockwise direction from the position shown in Fig. 1 until they are out of the path of the switch points. The switch points are then thrown to the desired position and the lock lugs are rotated in a counter-clockwise direction. As the lock lugs approach the switch points the guide surface 17 thereof engage the side faces of the switch points and cam the lock lugs into engagement until the lateral faces 18 of the lock lugs positively and directly engage the side faces of the switch points. The switch point lying against the stock rail is locked in position thereagainst by the adjacent lock lug and the other switch point which is spaced from the stock rail is held spaced therefrom by the lock lug adjacent thereto, as shown in Fig. 1. The switch points are then held in position and are not influenced by the passing of a train irrespective of its speed so that any possibility of the switch splitting is precluded. Moreover, the operativeness and inoperativeness of the control of the switch has no effect upon its position.

An important feature of the present invention resides in the fact that the forces which act upon the lock by reason of the passing of a train are prevented from setting up destructive stresses in any of its component parts. This is largely due to the slideable mounting of the rock shaft and the action of the coil spring 28 and its associated structure which permit the rails and the rock shaft as well as the rock shaft and the lock lugs to partake of relative movement to the extent necessary on the passing of a train.

When for instance the stock rails are spread or moved laterally by the passing of a train the operating bar 20 and the housing 31 each receive motion from the stock rail which is disposed adjacent thereto. The operating bar 20 is secured to the rock shaft and it carries the rock shaft with it in its movement. The motion of the rock shaft

through the action of the collar 29 which it carries at its outer end and the motion of the housing 31 through the action of its annular flange 32 compresses the coil spring 28 arranged between the collar and the flange. 70 As the stock rails spring back to their position after the train has passed the rock shaft and the housing under the influence of the coil spring resume their proper position.

I claim:

1. In a switch lock of the character described, in combination with stock rails and switch points, a rock shaft journaled in said stock rails to partake of rotary and transverse movement with respect thereto, a pair of lock lugs splined on said shaft, the members of said pair being arranged adjacent the respective switch points, a spacing sleeve carried by said shaft between said lugs, means for limiting the transverse movement of the rock shaft including a coil spring arranged upon the rock shaft and having one end abutting a stock rail and a collar secured to the rock shaft and abutting the opposite end of the rock shaft, operating means for said rock shaft, and locking means for said operating means.

2. In a switch lock of the character described, in combination with stock rails and switch points, a rock shaft journaled in said stock rails to partake of rotary and transverse movement with respect thereto, a pair of lock lugs splined on said shaft, the members of said pair being arranged adjacent the respective switch points, a spacing sleeve carried by said shaft between said lugs, means for limiting the transverse movement of the rock shaft, and operating means for said rock shaft.

3. In a switch lock of the character described, in combination with stock rails and switch points, a rock shaft journaled in said stock rails to partake of rotary and transverse movement with respect thereto, a pair of lock lugs splined on said shaft, the members of said pair being arranged adjacent the respective switch points, a spacing sleeve carried by said shaft between said lugs, and means for limiting the transverse movement of the rock shaft.

4. In a switch lock of the character described, in combination with stock rails and switch points, a rock shaft journaled in said stock rails to partake of rotary and transverse movement with respect thereto, a pair of lock lugs splined on said shaft, the members of said pair being arranged adjacent the respective switch points, and a spacing sleeve carried by said shaft between said lugs.

5. In a switch lock of the character described, in combination with stock rails and switch points, a rock shaft journaled in said stock rails, a lock lug carried by the rock shaft for engaging and locking a switch 130

- point, and operating means for said rock shaft, and locking means for said operating means.
6. In a switch lock of the character described, in combination with stock rails and switch points, a rock shaft journaled in said stock rails, a lock lug carried by the rock shaft for engaging and locking a switch point, and operating means for said rock shaft.
- 5 7. In a switch of the character described, in combination with stock rails and switch points, a rock shaft journaled in said stock rails, and a lock lug carried by the rock shaft for engaging and locking a switch point.
- 10 8. In a switch lock of the character described, in combination with the stock rails and switch points, a rock shaft journaled in said stock rails to partake of rotary and transverse movement with respect thereto, a lock lug splined on the rock shaft for engaging and locking each switch point, and means for limiting the transverse movement of the rock shaft including a coil spring arranged upon the rock shaft and having one end abutting a stock rail and a collar secured to the rock shaft and abutting the opposite end of the rock shaft.
- 15 9. In a switch lock of the character described, in combination with the stock rails and switch points, a rock shaft journaled in said stock rails to partake of rotary and transverse movement with respect thereto, a lock lug splined on the rock shaft for engaging and locking each switch point, and a spring means for limiting the transverse movement of the rock shaft including a coil spring arranged upon the rock shaft and having one end abutting a stock rail and a collar secured to the rock shaft and abutting the opposite end of the rock shaft.
- 20 10. In a switch lock of the character described, in combination with the stock rails and switch points, a rock shaft journaled in said stock rails to partake of rotary and transverse movement with respect thereto, a lock lug splined on the rock shaft for engaging and locking each switch point, and means for limiting the transverse movement of the rock shaft including a coil spring arranged upon the rock shaft and having one end abutting a stock rail and a collar secured to the rock shaft and abutting the opposite end of the rock shaft.
- 25 11. In a switch lock of the character described, in combination with the stock rails and switch points, a rock shaft journaled in said stock rails to partake of rotary and transverse movement with respect thereto, and a lock lug splined on the rock shaft for engaging and locking each switch point.
- 30 12. In a switch lock of the character described, in combination with the stock rails and switch points, a rock shaft journaled in said stock rails to partake of rotary and transverse movement with respect thereto, a lock lug splined on the rock shaft for engaging and locking each switch point, means for limiting the transverse movement of the rock shaft including a coil spring arranged upon the rock shaft and having one end abutting a stock rail and a collar secured to the rock shaft and abutting the opposite end of the rock shaft, and a housing for the coil spring and collar.
- 35 13. In a switch lock of the character described, in combination with stock rails and switch points, a lock lug for engaging and locking each of said switch points, said lock lug having an inclined guiding face for camming the lug lock into operative relation with respect to said switch point.
- 40 14. In a switch lock of the character described, in combination with stock rails and switch points, a rock shaft journaled in said stock rails to partake of rotary and transverse movements with respect thereto, and a lock lug carried by said rock shaft.
- 45 15. In a switch lock of the character described, in combination with stock rails and switch points, a rock shaft journaled in said stock rails to partake of rotary and transverse movements with respect thereto, a lock lug carried by said rock shaft, and means for operating said rock shaft including an operating bar and a keeper for said operating bar.

JULIUS HUGO SKOGMAN.
